WINDOW SHELF

May Harrison Biggers, Webster Groves, Mo.

Application April 23, 1935, Serial No. 17,820

1 Claim. (Cl. 211—114)

My invention has relation to improvements in shelves, more particularly those adapted to be attached to windows, and it consists in the novel features of construction more fully set forth in 5 the specification and pointed out in the claim.

The principal object of the present invention is to provide a shelf that may be quickly and easily attached to a window and so constructed as not to interfere with the opening and closing 10 of the window.

A further object is to provide a shelf for windows that may be easily applied and easily removed, requiring no alterations in the window for attachment thereto. It is a further object 15 of the invention to provide a window shelf that is simple and ornamental in appearance and at the same time capable of being manufactured at low cost. Other advantages inherent in the invention will be better apparent from a detailed 20 description thereof in connection with the accompanying drawing, in which:

Figure 1 is a perspective view of a window frame and sash showing my improved shelf applied to the sash; Fig. 2 is a vertical section 25 through the sash and shelf taken on the line 2—2 of Fig. 1; Fig. 3 is a top plan of one of the hangers for the shelf, a fragment of the shelf and window sash also being shown; Fig. 4 is a cross-sectional detail taken on the line 4—4 of Fig. 1; Fig. 5 30 is a side elevation of a modified form of hanger; Fig. 6 is a vertical section of a further modified form of hanger constructed for adjustability as to length; and Fig. 7 is a rear elevation of the 35 hanger shown in Fig. 6 with the upper and lower ends broken away.

Referring to the drawing, F represents a window frame and S a window sash slidably fitted therein. My improved window shelf comprises a pair of hangers 1, 1 carried by the top rail R 40 of the sash S, each of said hangers being bent to provide a loop or stirrup 2 at its lower end and a bifurcated flange 3, 3 at its upper end. The end 4 of the metal strap 5, of which the hanger is comprised, is preferably spot-welded at a to 45 the long member 6 of the hanger, and slightly above the end 4 the long member 6 has an opening 7 to receive a stud 8 projecting from an ornamental rosette 9. A brace member 10 is pivotally carried by the stud 8 and held thereon by a nut

11. The brace member 10 has its free end provided with teeth 12, the purpose of which is to engage and bite into the side rail 13 of the window sash and brace the shelf as a whole against longitudinal swaying movement. There is a brace 5 member 10 for each hanger 1 and when said brace members are in engagement with side rails 13, 13 (as shown dotted Fig. 1) the shelf is securely held in position.

In the forks 3, 3 comprising the bifurcated 10 flange there are holes o, o for positioning over the L-screws 14, 14 properly secured in the top of the rail R of the window sash S. The loops or stirrups 2, 2 of the hangers are adapted to receive a glass slab 15 which comprises the shelf 15 proper. As shown in Fig. 2 the shelf 15 rests against the window and inclines slightly to the rear so if there is a tendency for any articles on the shelf to slide they will slide against the window which will arrest them. 20

In Fig. 5 I show a modification of the shape of the hangers. In this form of the invention the hanger 16 is merely L-shaped having a horizontal component 17 with an upwardly turned end 18 in place of the loop or stirrup 2 of the 25 main form. The flange 19 at the upper end of the hanger is formed as in the main form.

In the modification shown in Figs. 6 and 7 the hanger 20 is identical with the hanger 1 of the main form, except that the long member is made 30 in two pieces 21 and 22, the former having an opening 23 and the latter a long slot 24 through which a stud 25 passes and is secured by a wing nut 26. By virtue of the stud and slot connection of the members 21 and 22 the hanger 20 is 35 adjustable vertically so that it may be adapted to any style of window.

Having described my invention, I claim:

A shelf for windows comprising a pair of 40 hangers suspended from the window sash, each of said hangers having a brace hinged to the hanger for lateral projection to engage with the sash, means at the upper end of the hangers for engagement with the sash, said hangers terminating at their lower ends in stirrups, a shelf member disposed in said stirrups, and means for adjusting the length of said hangers. 45

MAY HARRISON BIGGERS.
